Primary Examiner — Paula Allen Greene(57) **CLAIM**

The ornamental design for a combined earphones and headband, as shown and described.

DESCRIPTION

FIG. 1 is a perspective view of a combined earphones and headband showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the combined earphones and headband shown in an alternate position; and,

FIG. 10 is a perspective view of the combined earphones and headband shown in an alternate position.

The broken lines in FIGS. 9 and 10 showing a cable depict environment and form no part of the claimed design. The other broken lines in the drawings depict portions of the combined earphones and headband that form no part of the claimed design.

1 Claim, 10 Drawing Sheets(56)
